UNITED STATES PATENT OFFICE.

BRAXTON L. SCOTT, OF ARLINGTON, VIRGINIA.

TOY RACE COURSE.

Application filed May 12, 1928. Serial No. 277,118.

This invention relates to new and useful improvements in toy race courses and aims to provide a highly amusing and entertaining toy constructed and operated to simulate to a general extent an actual horse race.

An important object of this invention is to substantially improve upon or simplify devices of this general character, and with this in view the invention consists of a simple construction containing relatively few parts, and these co-related as to reduce the possibility of disarrangement to a minimum.

With the foregoing and other objects in view as the nature of the invention will be better understood, the same comprises the novel form, combination and arrangement of parts hereinafter more fully described, shown in the accompanying drawings and claimed.

In the accompanying drawings wherein like reference characters indicate corresponding parts throughout the same:

Figure 1 is a top plan view of the toy race horse.

Figure 2 is a detail longitudinal section thereof, the jockey-ridden race horse simulating figures being arranged at the starting point.

Figure 3 is a fragmentary longitudinal taken substantially upon the line 3—3 of Figure 2 disclosing more clearly the power means for rotating the figures upon the course.

Figure 4 is an edge elevation partially in cross section of the uppermost one of a plurality of superposed driven discs or plates provided with means for engaging the horse simulating figure carrying arms acting as a means to limit the manual movement of the figures in a reverse direction so that they may all start from a common point, this means also being provided for causing the simultaneous movements of all the figures in the proper direction.

Figure 5 is a fragmentary section through this disc or plate.

Figure 6 is a perspective of said member carried by the disc or plate.

Figure 7 is a top side perspective of one of the figure carrying arms.

Figure 8 is a fragmentary section through the figure moving spring motor disclosing in side elevation a manually controlled means whereby the motor may be stopped in an abrupt manner.

Figure 9 is a vertical fragmentary section

taken substantially upon the line 9—9 of the Figure 8, and

Figure 10 is an end elevation of the spring motor disclosing the ratchet means whereby the spring of the motor is prevented from becoming unwound until the manual means has been released.

Now having particular reference to the drawings, my toy race course consists of a circular plate 5 to simulate generally a race track supported by suitable feet 6 and having suitable markings upon its top surface as indicated in Figure 1 to designate the quarter, half, three-quarter, and mile post of a race track.

Secured to the under side of this plate 5 at opposed points and adjacent the edge of the plate are hangers 7 and 8, the hanger 7 being constructed with a relatively large circular bearing, while the hanger 8 is equipped with a relatively small circular bearing, as disclosed in Figure 3.

The motor unit of the device consists of a tubular shaft 9 having closure blocks 10 and 11 secured within opposite ends thereof, one end of this shaft being journaled within the large bearing of the hanger 7, while the outer end of the block 11 at the opposite end of the shaft is equipped with a pintle 12 journaled and secured within the hanger 8 as disclosed in Figure 3.

Located within this tubular shaft 9 is an elongated coiled spring 13, the inner end thereof being anchored to the adjacent block 11, while the outer end of said spring is secured to the inner end of a longitudinally extending stub shaft 14, loosely arranged within a longitudinal opening in the outer closure block 10 of said shaft and upon the outer end of which stub shaft is arranged a suitable handle 15.

Directly at the outer face of the block 10 said stub shaft 14 is equipped with a suitable ratchet member 16, while depending from the supporting hanger 7 at the edge of the plate 5 is a ratchet dog 17. This prevents the unwinding of the spring after and during the winding of the spring by rotating the handle 15.

Adjacent the opposite end of the tubular shaft 9 the same is equipped externally with a lug 18, while slidably arranged within suitable guide means 19 beneath the plate 5 is a trigger member 20, the inner end of which is constructed for engagement with said lug 18, when the trigger is moved inwardly to prevent rotation of the tubular shaft 9 under the ac-

tion of the spring 13 therein. This trigger is constructed at its outer end with a finger hole 21, while said trigger is normally forced inwardly for engagement with the lug 18 through the medium of a coiled spring 22. Secured within an opening in the center of the plate 5 directly above the spring motor is an upwardly extending tubular shaft housing 23 rotatable within which is a shaft 24, the lower end being beneath the plate 5 and being equipped with a small beveled gear 25, which gear has mesh with the gear 26 arranged upon the tubular shaft 9, see Figure 3.

The upper end of the shaft 24 extends considerably above the housing 23, and is screw threaded as shown in Figure 2. Secured on this threaded end of the shaft are superposed spaced discs 27 preferably three in number, and of reduced diameter from the uppermost one to the lowest as in Figure 2. The invention further consists of three horse-figure supporting arms, each of which is designated by the reference character 28. Each arm is formed adjacent its inner end with an opening 29 for loose engagement upon the shaft 24 beneath the respective discs 27. These openings of the arms are so located that the inner ends of the arms will terminate in slight spaced relation with the edges of the discs as disclosed.

Furthermore, the inner end of each arm is formed or equipped with an upwardly extending finger 30 for frictional engagement with the under side of the adjacent disc, while arranged upon the shaft 24 directly beneath and larger than the openings in the said arms are arm supporting washers 31. The outer ends of these arms are formed with vertical extensions 32 while arranged upon the upper ends thereof are jockey-ridden horse simulating figures 33, said extensions being of varying length so that all the figures will be in the same horizontal plane. Obviously, therefore, the fingers 30 upon the inner ends of the arms 28 will frictionally bear against the discs 27 to prevent the sagging of the outer figure carrying ends of said arms. Adjacent the edge of the uppermost disc 27, said disc is formed with a slot 34 within which is pivoted the upper end of a depending lever 35, the upper end of this lever above said disc 27 being equipped with a horizontal nose piece 36 for preventing the swinging of the lever in a clockwise direction, but to permit said lever to swing in an anti-clockwise direction, as suggested by the dotted lines in Figure 4. The length of this lever 35 is such as to encounter all of the arms 28 so that the manual movement of the arms in a clockwise direction will be limited with the end in view of enabling the figures to be manually arranged in an alined starting position.

Assuming the horses to be in the starting position as indicated in Figure 2, and the spring 13 of the motor 2 have been wound,

the releasing of the trigger 20 will result in the turning of the tubular shaft 9, and consequently the shaft 24. The lever 35 traveling in a counter-clockwise direction will engage with all of the arms 28 to effect the rotation thereof while the upstanding fingers 30 will cooperate with the respective discs to properly balance the arms during the rotation of the latter. The engagement of the lever 35 with the figure arms assures a simultaneous start of all the figures. As soon as sufficient momentum has been imparted to the figures, the trigger 20 is released for stopping the rotation of the tubular shaft 9.

However due to the momentum gained by the figures, they will continue to rotate notwithstanding frictional engagement of the inner ends of the arms 28 with said discs 27. This continued rotation will absolutely place the figures in various positions, and the figures stopping nearest the mile post, or other designated point, will be considered as having won the race.

In view of the lever 35 being pivoted, and permitted to swing in the direction of the dotted lines in Figure 4, the arms during their continued rotation after the discs have been stopped will ratchet past said lever in an obvious manner.

It will thus be seen that I have provided a novel, simple, and extremely amusing toy race course that is well adapted for all the purposes heretofore designated, even though I have herein shown and described the invention as consisting of certain detail structural elements, it is nevertheless to be understood that minor changes may be made therein without affecting the spirit and scope of the appended claims.

Having thus described the invention, what I claim as new and desire to secure by Letters Patent is:—

1. In a toy race course of the class described, a race track simulating a base, a shaft journaled through the central portion of the base and projecting thereabove, a disc secured on the shaft above the base for rotation therewith, a horizontal arm loosely arranged upon the shaft beneath the disc, a figure arranged upon one end of the arm, and a projection extending upwardly from the other end of the arm for engagement with the disc to balance said arm, and means depending from and loosely associated with the disc for engagement with the arm to start the horizontal swinging movement of the arm when the shaft and disc is rotated, said means being mounted for swinging movement in one direction only to permit the figure supporting arm to ratchet over said means during the rotation of the arm after the disc has stopped.

2. In a toy race course of the class described, a race track simulating a base, a shaft journaled through the central portion of the

base and projecting thereabove, a disc secured on the shaft above the base for rotation therewith, a horizontal arm loosely arranged upon the shaft beneath the disc, a figure arranged upon one end of the arm, and a projection extending upwardly from the other end of the arm for engagement with the disc to balance said arm, and means depending from and loosely associated with the disc for engagement with the arm to start the horizontal swinging movement of the arm when the shaft and disc is rotated, said means being mounted for swinging movement in one direction only to permit the figure supporting arm to ratchet over said means during the rotation of the arm after the disc has stopped, said means comprising a lever pivoted at its upper end and formed with a laterally disposed nose for engagement with the disc to prevent the swinging of the lever in a clockwise direction.

3. In a toy race course of the class described, a race track simulating a base, a shaft journaled through the central portion of the base and projecting thereabove, a disc secured on the shaft above the base for rotation therewith, a horizontal arm loosely arranged upon the shaft beneath the disc, a figure arranged upon one end of the arm, and a projection extending upwardly from the other end of the arm for engagement with the disc to balance said arm, and means depending from and loosely associated with the disc for engagement with the arm to start the horizontal swinging movement of the arm when the shaft and disc is rotated, said means being mounted for swinging movement in one direction only to permit the figure supporting arm to ratchet over said means during the rotation of the arm after the disc has stopped, and a spring motor operatively associated with the shaft for driving the same.

4. In a toy race course of the class described, a race track simulating a base, a shaft journaled through the central portion of the base and projecting thereabove, a disc secured on the shaft above the base for rotation therewith, a horizontal arm loosely arranged upon the shaft beneath the disc, a figure arranged upon one end of the arm, and a projection extending upwardly from the other end of the arm for engagement with the disc to balance said arm, and means depending from and loosely associated with the disc for engagement with the arm to start the horizontal swinging movement of the arm when the shaft and disc is rotated, said means being mounted for swinging movement in one direction only to permit the figure supporting arm to ratchet over said means during the rotation of the arm after the disc has stopped, and a spring motor operatively associated with the shaft for driving the same, this spring motor including a spring driven tubular shaft mounted for rotation beneath the

track simulating base, and manually releasable means for normally maintaining the tubular shaft against rotation during the winding of the spring.

5. In a toy race course of the class described, a race track simulating a base, a vertical shaft journaled at its lower end through the central portion of the base, a plurality of vertically spaced discs secured on the shaft above the base for rotation therewith, said discs gradually decreasing in size from the top to the lowermost one, a horizontal arm loosely arranged upon the shaft beneath each disc, an upstanding finger formed on the inner end of each arm for engagement with the under face of each disc to balance said arms, a figure supported on the outer end of each arm, means depending from and loosely associated with the uppermost disc for engagement with all of the arms for arranging the same at a common starting point and further starting the rotation of the arms and the shaft and said discs are rotated, means for rotating the shaft and the disc, said first mentioned means being mounted for swinging movement in one direction only to permit the arms to ratchet past said means during the rotation of the arms after the discs have stopped, the weight of the figures causing the continued rotation of the arms after the discs have stopped.

6. In a toy race course of the class described, a race track simulating a base, a vertical shaft journaled at its lower end through the central portion of the base, a plurality of vertically spaced discs secured on the shaft above the base for rotation therewith, said discs gradually decreasing in size from the top to the lowermost one, a horizontal arm loosely arranged upon the shaft beneath each disc, an upstanding finger formed on the inner end of each arm for engagement with the under face of each disc to balance said arms, a figure supported on the outer end of each arm, means depending from and loosely associated with the uppermost disc for engagement with all of the arms for arranging the same at a common starting point and further starting the rotation of the arms and the shaft and said discs are rotated, means for rotating the shaft and the disc, said first mentioned means being mounted for swinging movement in one direction only to permit the arms to ratchet past said means during the rotation of the arms after the discs have stopped, the weight of the figures causing the continued rotation of the arms after the discs have stopped, said arms actuating means comprising a lever having its upper end extending through a slot formed in the uppermost disc, the upper end of the lever being pivotally mounted on said uppermost disc, and a laterally extending nose formed on the pivoted upper end of the lever for engagement with the upper face of the

uppermost disc to permit swinging movement of the lever in only one direction.

7. In a device of the class described, a base, a shaft extending vertically through the central portion of the base, means arranged on the shaft above the base for rotation therewith, means arranged beneath the base for driving said shaft, said means comprising a tubular shaft supported horizontally beneath the base, intermeshing gears arranged on said tubular shaft and the lower

end of the vertical shaft, a windable spring arranged in the tubular shaft for effecting the rotation thereof, a projection extending from one side of the tubular shaft, and manually releasable means arranged on the bottom of the base for cooperation with the projections to normally lock the tubular shaft against rotation. 15

In testimony whereof I affix my signature.

BRAXTON L. SCOTT.
